UNITED STATES PATENT OFFICE.

LESLIE PROBYN, OF FREETOWN, SIERRA LEONE.

TOBACCO-PIPE, CIGAR-HOLDER, AND CIGARETTE-HOLDER.

No. 809,325.

Specification of Letters Patent.

Patented Jan. 9, 1906.

Application filed February 16, 1905. Serial No. 245,801.

To all whom it may concern:

Be it known that I, LESLIE PROBYN, a subject of the King of Great Britain, residing at Freetown, Sierra Leone, have invented certain new and useful Improvements in Tobacco-Pipes, Cigar-Holders, and Cigarette-Holders, of which the following is a full, clear, and exact description.

The invention relates to pipes, cigar-holders, and cigarette-holders of the hookah type, in which the smoke passes through a liquid or filtering medium, or both combined, and in which the hookah part may be used at will or not.

15 The object of the present invention is to simplify the construction of such a pipe, cigar or cigarette holder.

The invention is illustrated in the accompanying drawings, in which—

20 Figure 1 is a vertical longitudinal section of one form of a cigar or cigarette holder of the hookah type. Fig. 2 is a vertical longitudinal section, and Fig. 3 is a plan, of another form of cigar or cigarette holder with the mouthpiece removed. Figs. 4 and 5 are respectively a vertical longitudinal section and plan of another form of cigar or cigarette holder. Figs. 6, 7, 8, and 9 show another modification of a cigar or cigarette holder,

25 Fig. 6 being a vertical section of the complete apparatus with the water-chamber and mouthpiece removed, Fig. 7 being a side elevation of the upper part of said apparatus, and Fig. 8 a side elevation of the lower part thereof. Fig. 9 is a plan of the lower part separately.

30 Fig. 10 is a longitudinal vertical section of a pipe, showing still another modification; and Fig. 11 is a side elevation of the lower part thereof. Fig. 12 is a plan of the lower portion shown separately.

35 Although in all the figures except Figs. 10, 11, and 12 I have shown cigar or cigarette holders, it will be understood that it is only necessary to substitute a bowl for the holder to make any of the forms into a pipe.

In all the forms of apparatus shown the water-chamber may be closed to prevent the water escaping when the apparatus is carried in the pocket or laid on its side; but I am 40 aware that this feature is not a novelty separately considered.

In all the forms of apparatus shown the smoke may be caused to pass through the water or other liquid or direct to the mouth-piece, as desired.

45 In the apparatus shown in Fig. 1 the smoke

passes from the holder *a* along the stem *b* a certain distance and then passes out through an opening *b'* in the under side thereof. The bore leading from the mouthpiece *c*, after 50 passing a certain distance along the stem *b*, passes out through another opening *b''*, adjacent to the first-mentioned opening *b'*. These two openings are arranged to coincide with two passages *d' d''* through a plug or stopper *d*, which passages pass into the body of the plug or stopper and out through opposite sides thereof. The plug or stopper *d* fits a ring or socket *e*, carried by the upper part of a chamber *f*, preferably made of glass. The said ring 55 or socket *e* has two passages *e' e''* in opposite sides thereof, one of which is continued by means of a tube *f'* to the lower part of the chamber *f*. The end of this tube is formed with downwardly-extending points or projections 60 *f''*, thus causing the smoke to escape into the water at more than one point. This chamber *f* may be partly filled with water or other liquid, and it may be provided with one or more diaphragms made of fine gauze or other suitable filtering material or with a bundle of straws or quills *f''*, filling a section of the chamber *f* and arranged vertically to the level of the liquid. The lower part of the chamber may contain small pieces of pumice-stone or 65 other suitable material *g*. One of the diaphragms or bundles *f''* should be above and one should be below the level *h* of the liquid. The chamber *f* is preferably in the form of a tube closed at its lower end. This tubular 70 chamber may be provided with a bulb enlargement *f''* at its lower end and with a similar enlargement about midway between the lower enlargement and its upper end. In order to insure a tight joint between the two bores, the 75 one leading from the holder and the other from the mouthpiece, and the two passages in the plug or stopper *d*, one of the parts is fitted with two short tubes *b' b''*, entering the openings in the other part. The plug or stopper *d* may be partly turned round in its socket *e*, thereby cutting off communication between the interior and exterior of the cooling and filtering chamber *f*, as the passages *d' d''* and *e' e''* in the two parts *d* and *e* will no longer coincide. The cooling and filtering chamber *f* is 80 preferably arranged as near to the mouth-piece end of the pipe as convenient and at such an angle to the stem that the chamber will be approximately vertical when the pipe 85 is held in the mouth.

Instead of forming the stopper *d* as above

described I may form it with two passages d^3 5, passing through it vertically, as shown in Figs. 2 and 3. These passages are continued for a short distance above the stopper by means of two tubes d^5 d^6 , which fit into the enlarged ends of the two openings b' b^2 on the under side of the stem b , above described. When it is desired to prevent the water from escaping, the stopper d is removed from the stem b , turned partly round, and replaced by putting the two tubes d^5 d^6 into two cavities i , provided in the stem for that purpose. Similarly the short tubes d^5 d^6 may be made to project from the stem b and to fit into holes 15 and cavities in the stopper.

The upper surface of the plug d (shown in Figs. 1, 2, and 3) is formed with a passage o , as shown more clearly in Figs. 8 and 9, or it may be formed with a groove o^2 , acting as 20 a passage, as shown in Figs. 10 and 12, so that the smoke may be caused to pass direct from the holder a to the mouthpiece c , as herein-after described.

Another method by which the water can be 25 prevented at will from escaping from the chamber f holding the liquid and the smoke allowed to pass direct from the holder to the mouthpiece is to make the stopper longer, as shown in Figs. 4 and 5. A ring j is made, 30 from the outside of which and in diametrically opposite directions two tubes project. One of the tubes terminates in the mouthpiece c and the other in the holder a . The passages from mouthpiece c and from holder 35 a pass through the ring j . Thus these passages end in two holes j' in the inner surface of the ring, such holes being exactly opposite one another. The stopper e is then placed through the ring j , which it must fit exactly. Owing 40 to its length, part of the stopper will pass sufficiently through and beyond the ring j to enable it to act as stopper to the liquid-holding chamber f . At the two points on the exterior surface of the stopper which face the 45 ends of the two passages j' , above described, two holes e^3 e^4 are made in a downwardly-sloping direction. The two holes pass downward vertically through the stopper e to the base thereof. One passage e^3 is then continued 50 by a tube f' to the lower part of the liquid-holding chamber f , as already described. In addition to the two passages above described a direct passage e^5 is made through the stopper. This direct passage passes through 55 the stopper at same level as the two entrances to the two passages e^3 e^4 , above described; but its ends are at about right angles to the other entrances. It will be noticed that when the entrances to the two passages e^3 e^4 coincide 60 with the mouths of the holes j' in the inner surface of the ring a continuous air-passage is made between the holder a through the stopper e , then down into and through the liquid, then up again through the stopper e , 65 and thence to the mouthpiece c . If the stop-

per e is given a quarter-turn, communication with the liquid is cut off and continuous communication is established between the holder a and the mouthpiece c by means of the passage e^5 through the stopper. At the top of 70 the stopper a handle e^6 is fixed, which should project slightly over the sides of the ring j . This handle e^6 serves, first, as the means whereby the stopper e can be twisted, and, secondly, to prevent the stopper from falling 75 through the ring j . The mouthpiece c is preferably fixed at such an angle that the chamber will be approximately vertical when the pipe is held in the mouth.

In all the forms hereinbefore referred to 80 the parts are merely held together by friction. In Figs. 1 and 2 a tube l is employed for this purpose. In the remaining figures some more definite method of connecting the parts is shown.

In Figs. 6, 7, 8, and 9 the parts are held together by a bayonet-catch or double incline. The stem b of the holder has two downwardly-projecting pieces m , each having an inwardly-projecting flange m' . The plug d has two 90 lateral flanges n , each having double inclines n' and a central stop n^2 . When the plug d is placed in position and turned in one direction, as shown in Fig. 6, the two parts b and d are securely fastened together by two of the inclines n' , and the smoke passes down into the water-chamber through the passage b' , hole d^7 , tube f' , and thence to the mouthpiece by the hole d^8 and passage b^2 . It will be noticed that the plug d has a passage o therein terminating in the holes o' . When the plug d is turned in the opposite direction to that shown in Fig. 6, it is secured by the other two inclines n' and the holes o' are coincident with the holes b' b^2 , and the smoke can then pass 100 direct from the holder a through the hole b' , through the passage o to the hole b^2 , leading to the mouthpiece. When the parts are in the position last described, the holes d^7 d^8 , leading from the water-chamber, are stopped, 110 as their upper ends are against a solid surface on the under side of the part b . The plug d has a central boss p , entering a hole in the stem b .

The apparatus shown in Figs. 10, 11, and 115 12 is a modification of that shown in Figs. 6, 7, 8, and 9; but it is shown applied to a pipe. In this form of the invention two pins p' are carried by a downwardly-extending portion of the stem b , which pins engage under double inclines q , carried by the plug d , and thus secure the parts firmly together. The pins p' 120 may engage under either of the inclines q . When in one position—that shown in Fig. 10—the smoke passes down through the liquid and 125 out of the mouthpiece. When the parts are turned so that the pins p' engage under the other inclines, the grooves o^2 will connect the bores b' and b^2 and the smoke will pass from the bowl to the mouthpiece without passing 130

through the water. At the same time the tops of the holes d^7 and d^8 will come under solid portions of the stem and being held in contact therewith no liquid will be able to escape.

If desired, the central portion of the pipe may be entirely removed, and the mouthpiece end c , having the boss c' , may be inserted direct in the cavity b^4 , which is made to receive either it or the boss b^5 , carried by the portion b .

I do not limit myself to the forms of stopper hereinbefore described, as any stopper may be employed which will provide communication between the holder or bowl, liquid-chamber, and mouthpiece in one position, will cut off communication between the interior and exterior of the liquid-chamber when partly rotated, and will at the same time provide a direct passage from the holder or bowl to the mouthpiece.

Having fully described my invention, what I claim, and desire to secure by Letters Patent, is—

1. In an apparatus for smoking tobacco, the combination of a holder, a mouthpiece and passages leading from same, a plug having two passages therein, the upper ends of which are adapted in one position to coincide with the passages leading from the holder and mouthpiece, the lower ends of which lead to a liquid-chamber and cause the smoke to pass

through the liquid, a cross-passage in said plug intermediate of the other two passages and adapted in one position to directly connect the 35 passages leading from the holder and mouthpiece, a liquid-chamber carried by said plug and adapted to be turned and to assume two positions at right angles to each other, substantially as set forth.

2. In an apparatus for smoking tobacco, the combination of a holder, a mouthpiece, passages leading from said mouthpiece, a plug having two passages therein the upper ends of which are adapted in one position to register with the passages leading from the holder and mouthpiece the lower ends of which lead to a liquid-chamber and cause the smoke to pass through the liquid, a cross-passage in said 45 plug intermediate of the other two passages 50 and adapted in one position to directly connect the passages leading from the holder and mouthpiece, a liquid-chamber carried by said plug and adapted to be turned to assume two positions at right angles to each other and 55 stops to limit the motion of said plug, substantially as described.

In witness whereof I have hereunto set my hand in presence of two witnesses.

LESLIE PROBYN.
